UNITED STATES PATENT OFFICE.

FRIEDRICH JOHANN KALKOW, OF OFFENBACH-ON-THE-MAIN, GERMANY.

MANUFACTURE OF LEAD SALTS OF ACETIC ACID.

1,097,099.

Specification of Letters Patent. Patented May 19, 1914.

Application filed January 18, 1913. Serial No. 742,794.

To all whom it may concern:

Be it known that I, FRIEDRICH JOHANN KALKOW, doctor of philosophy, a citizen of the German Empire, and resident of Offenbach-on-the-Main, in the Grand Duchy of Hesse, Germany, (with the post-office address Frankfurterstrasse 61,) have invented new and useful Improvements in the Manufacture of Lead Salts of Acetic Acid, of 10 which the following is a specification.

This invention relates to a process for the manufacture of lead salts of acetic acid from lead, using air as an oxidant and either acetic acid or an aqueous solution of normal 15 lead acetate as solvent.

There is a process known which produces lead acetate from lead, acetic acid and air, wherein the mass of lead is kept immersed in acetic acid during the treatment with air 20 under pressure. The complete covering of the mass with liquid, however, is an unfavorable condition for the following reason: Since lead can only be oxidized and therefore dissolved where it is in contact with 25 air, and since by covering the whole heap of lead with liquid one cuts off the air from the lead, only the bubbles of air rising through the liquid can effect oxidation and dissolution. The air quickly eats for itself a passage 30 through the lead and during the rest of the operation it travels through these passages without doing any further appreciable work in dissolving lead. Rapidity of dissolution is only to be noted in a freshly charged 35 apparatus where lead is present in excess; in continued operation the action sinks to practically nothing.

According to the present invention a rapid dissolution is continuously obtained if the 40 heap of lead is not covered with liquid but is provided with only sufficient liquid to insure that the current of air blown through it will carry up particles of liquid and thus continuously sprinkle the lead lying above 45 the surface of the liquid. Under these conditions the liquid becomes saturated with basic lead acetate in a short time and so much hydrated oxid is formed on the lead that fresh solvent added after a short time 50 becomes saturated in a short time.

By the present invention the liquid is con-

verted into foam by the air under pressure so that there is a particularly intimate contact of the solvent and air with the metal.

The accompanying drawing is a vertical 55 section through an apparatus suitable for practising this invention.

In the vessel 1 the mass of lead 2 is supported on a grating 3. The solvent 4 is on the bottom of the vessel and in the construction shown the surface of the liquid is just below the grating 3, although the level of the liquid may vary within certain limits. Through pipe 5 air under pressure is admitted into the liquid and in rising there- 60 through carries liquid with it, as indicated in the drawing, into the mass of lead which it sprinkles as it flows back to the bottom of the vessel. The compressed air leaves the vessel through a pipe provided with a safety 65 valve 6. The liquid may be withdrawn through the pipe 7. It is preferable to empty the vessel of liquid by admitting compressed air through a pipe 8. A manometer 9 indicates the pressure. 75

What I claim is:

1. The process of forming lead acetate, which consists in subjecting sub-divided metallic lead to the action of air currents and a suitable liquid reagent carried by said air 80 currents in the form of spray.

2. The process of forming lead acetate, which consists in subjecting sub-divided metallic lead to the action of air currents moving upwardly through the mass of lead and 85 entraining a suitable liquid reagent in said air currents in the form of spray.

3. The process of forming lead acetate, which consists in confining sub-divided lead in a reaction vessel, maintaining a body of 90 liquid reagent in the bottom of said vessel, and injecting jets of air through said liquid reagent and the lead, whereby the lead is sprayed with the reagent.

In testimony, that I claim the foregoing 95 as my invention, I have signed my name in presence of two witnesses, this seventh day of January, 1913.

FRIEDRICH JOHANN KALKOW.
